Patented Feb. 27, 1973

226,383

DENTAL X-RAY COLLATOR/INDEX

Anne E. Loughran, Centralia, Ill., assignor to Thann
Products Company, St. Louis, Mo.

Filed Jan. 28, 1972, Ser. No. 221,853

Term of patent 14 years

Int. Cl. D24—02

U.S. Cl. D24—1 R

FIG. 4

FIG. 1 is a front elevation of a dental X-ray collator/index, showing my new design;

FIG. 2 is a rear elevation thereof;

FIG. 3 is an enlarged cross-section taken on line 3—3 of FIG. 1; and

FIG. 4 is a rear elevation of a modified form of the design illustrated in FIG. 2.

I claim:

The ornamental design for a dental X-ray collator/index, substantially as shown and described.
